UNITED STATES PATENT OFFICE

HARRY C. GRAHAM, OF CORAOPOLIS HEIGHTS, PENNSYLVANIA

RAIL JOINT

Application filed August 11, 1931. Serial No. 556,347.

This invention relates to the securing together of lengths of rail in a railway, and consists in a fastening device which is simple and susceptible to cheap manufacture, is easy of application, secure in service, and easy of removal.

In the accompanying drawing, Figs. I and II show in perspective the fastening device in application to railway rails, with variation in detail. Figs. III and IV are views in section of the fish-plates of the two structures.

Referring, first, to Fig. I, a railway rail 1 is shown, having assembled with it opposite fish-plates 2, and a connecting bolt 3—all of which is the usual assembly. The shank of the bolt is slotted. The fish-plate is, on its outer face, provided with an outstanding eminence or boss; in this instance the fish-plate is ridged longitudinally with two ridges 20, 20 and the perforation through which the bolt extends is formed through the web of the fish-plate, intermediate the two ridges.

Aligned slots are cut in the two ridges and the slots are preferably made continuous by 25 extending into the web between the ridges, and the groove 5 so formed (cf. Fig. II) is in its position diametrical with respect to the bolt-hole. The bottom of the groove is oblique with respect to the axis of the bolt when assembly is completed. A wedge-key 4 with opposite relatively inclined surfaces is introduced into the otherwise complete assembly, engaging, along one edge, the bottom 30 of the groove 5 and, along the opposite edge, the outer limiting wall of the slot in the shank of the bolt. The shape and proportions are preferably such that the strain exerted on the bolt is truly axial in direction. The positions of the assembled parts are illustrated in 35 Fig. I. And it will be perceived that as the wedge-key is driven home the device is made secure. The parts may continue by friction in their so tightened positions, or the key may be locked in place by bending aside its 40 protuding tip. Loosening is effected by driving the key out again.

It will be perceived that, as the wedge-key is driven home, it is subjected to strains tending to bend it in the plane of its extent. Such 45 bending, with binding contacts on its oppo-

site wedge surfaces, may be effective in increasing its security in place.

The device as shown in Fig. II differs, in that a single and relatively broad ridge 6 is formed upon the outer face of the fish-plate, 55 through the middle portion of which the bolt-hole is formed. As in the other case, this ridge is grooved, and the groove 7 extends obliquely across the ridge from side to side and is in its location diametrical with respect 60 to the bolt-hole. The bottom of the groove is oblique to the bolt axis, as in the other case. In other respect the assembly is the same as that of Fig. I, and the method of applying and removing is the same.

In both cases the grooves (5, 7) are so inclined to the longitudinal extent of the fish-plate and rail that they are most easily accessible for application and removal.

I claim as my invention:

1. Means for joining together the rails of a railway including a fish-plate adapted to be arranged between and to engage the heads and the bases of two rails set end to end, such fish-plate being formed with a boss on its outer side, the fish-plate being perforate, and being in its bossed portion grooved with a groove which extends in diametrical direction with respect to such perforation, a bolt 75 with slotted shank adapted to penetrate a 80 bolt-hole in the web of a rail to which such fish-plate is applied and to penetrate at the same time the perforation in the fish-plate so applied, and a wedge key with opposite 85 relatively oblique surfaces adapted to be applied to an assembly of fish-plate and bolt to a rail, and to engage simultaneously, upon 90 its said opposite surfaces, the slot in the bolt and the groove in the bossed portion of the fish-plate.

2. Means for joining together the rails of a railway including a fish-plate adapted to be arranged between and to engage the heads and the bases of two rails set end to end, such fish-plate being ridged on its outer side, the fish-plate being perforate, and being in its 95 ridged portion grooved with a groove which extends in diametrical direction with respect to such perforation and the bottom of the groove being oblique in its extent with respect 100

to the axis of such perforation, a bolt with slotted shank adapted to penetrate a bolt-hole in the web of a rail to which such fish-plate is applied and to penetrate at the same time the perforation in the fish-plate so applied, and a wedge key with opposite relatively oblique surfaces adapted to be applied to an assembly of fish-plate and bolt to a rail, and to engage simultaneously, upon its said opposite surfaces, the slot in the bolt and the groove in the ridged portion of the fish-plate.

In testimony whereof I have hereunto set my hand.

16 HARRY C. GRAHAM.
